UNITED STATES PATENT OFFICE.

NORMAN E. PHILLIPS AND JAMES E. MATHERS, OF WASHINGTON, DISTRICT OF COLUMBIA.

DIRIGIBLE HEADLIGHT FOR AUTOMOBILES.

Application filed February 11, 1922. Serial No. 535,831.

To all whom it may concern:

Be it known that we, NORMAN E. PHILLIPS and JAMES E. MATHERS, citizens of the United States, residing at 507 E St. and 511 5 Fifth St. NE., respectively, Washington, District of Columbia, have invented certain new and useful Improvements in Dirigible Headlights for Automobiles, of which the following is a specification.

10 This invention relates to means for illuminating the roadway in front of an advancing automobile, and is especially directed to the novel means of automatically directing the rays of light from a dirigible headlight 15 into the zone of travel, as the automobile passes over a curved section of the roadway.

Other objects and advantages of the invention will hereinafter appear, and the 20 novel features thereof will be pointed out in the appended claims.

The invention is clearly illustrated in the accompanying drawings which, with the numerals of reference marked thereon, form a 25 part of this specification, and in which:

Fig. 1 is a front elevation of a portion of an automobile equipped with this invention.

Fig. 2 is an enlarged view of the lamp case, partly in section, showing the movable 30 reflector.

Fig. 3 is an enlarged detail view of the lower wall of the lamp case showing the reflector locking mechanism.

Fig. 4 is a plan view of the locking mechanism shown in Fig. 3.

Fig. 5 is an enlarged detail view in perspective of the reflector operating mechanism attached to the hinge knuckle of an automobile axle.

40 Like numerals of reference indicate like parts throughout the different views.

Referring to the drawings:

1 designates a lamp case rigidly mounted on the upright 2, at the front end of the automobile frame. A movable reflector 3 is 45 mounted within the lamp case 1, to admit of oscillating movement in a horizontal plane. Located within the reflector 3 is a lamp socket 4, into which may be mounted a lamp 5, which at proper times is lighted by means of an electric current led thereto by the wires 6, from any source of electric energy (not shown).

The reflector 3, may be of any desired

shape or design which can be adapted to 55 carry out the purposes of this invention; and with that object in view, the front end thereof is mounted on pivots at 7 and 8 positioned at the top and bottom of the front end of the lamp case.

60 This invention consists in providing means whereby the reflector 3, will be caused to automatically swing on its pivots in the direction of, and as the automobile is caused to deviate from a straight course. To provide means for actuating the movement of the reflector 3, the lower pivot 8, is extended outside of the lamp case 1, and its lower end 9, is suitably formed for attachment with the end of the transmission cable 10, by 70 means well known in the art.

The opposite end of the cable 10, is similarly connected to the projecting end 11, of the stub shaft 12. The stub shaft 12, is rotatively mounted in the journal 13, of the 75 bracket 14. The bracket 14, is rigidly mounted on the axle bar 15. Mounted on the lower end of the stub shaft 12, and adapted to rotate therewith, is the pinion gear 16. Meshing with the pinion gear 16, 80 is the rack 17, which is pivotally connected at the one end thereof, on the vertically projecting stud 18, which is mounted on the bracket 19. The bracket 19, is rigidly mounted on the hinge knuckle member 20 85 of the axle arm 21.

The axle arm 21, is mounted between the stationary knuckle members 22, of the axle bar member 15, and is adapted for oscillating movement in a horizontal plane well known 90 in the art.

95 It will be obvious to those skilled in the art, that as the axle arm 21, is oscillated through the operation of the steering mechanism of the automobile in the act of diverging its path of travel from a straight line, there will be a corresponding movement of the stud member 18, which will cause a reciprocal movement of the rack member 17. The rack member 17, being in mesh with the 100 pinion 16, a reciprocal movement of the rack member 17, will impart a rotative movement to the stub shaft 12. This movement transmitted through the cable 10, imparts a like rotative movement to the pivot member 8, 105 upon which the reflector 3 is mounted, with the resulting effect that as the axle arm 21, is moved to deflect the course of the auto-

mobile, there will be a corresponding movement to the reflector 3, causing a beam of light to be projected in the direction in which the course of the automobile is deflected.

The transmission cable 10, is detachably connected at the upper end with the projection 9, of the pivot 8, and at its lower end with the projection 11 of the stub shaft 12, by means of a form of coupling well known in the art, and by means of which the transmission cable 10, may be readily detached to adjust the synchronizing movement of the reflector and the shaft 12. Further means for adjusting the timing of the movement of the reflector 3, with the movement of the axle arm 21, is provided by the method of mounting the rack member 17, which admits of being moved outwardly from the 20 pinion gear 16, until it ceases to be in mesh therewith and while held in this position, the pinion gear 16, may be turned to advance or retard its cycle of rotation, and the rack member 17, again placed in actuating mesh therewith. To maintain the rack member 25 17, in position of mesh with the pinion gear 16, there is provided the spring 30.

To provide means for holding the reflector 3, in a fixed position, in case it is desired to 30 disconnect the cable 10, or in case of breakage or accident to the operating mechanism of the reflector, there is provided as shown in Figs. 3 and 4 an extended arm 23 rigidly attached to the pivot 8, having at its extended end a vertically movable stop 24, adapted to be positioned in the socket 25, formed in the lower wall of the lamp case 1.

The stop 24, is adapted to be yieldingly held in the socket 25 by the leaf spring 26, 40 attached to the extension arm 23, at the one end, and engaging the stop 24, and the finger lever 27, at the other end. With the lever 27, in the position shown in Fig. 2, the reflector 3, will be rigidly fixed in a central position 45 within the lamp case. With the lever 27, in the position shown in Fig. 3, the reflector 3, will be free to swing on its pivots 7, and 8.

It has been found important that to properly illuminate the path over which an advancing automobile is passing, especially where such path may diverge from an otherwise direct course, that the rays of light from the illuminating means be so deflected as to cover the whole sector of the curved road 50 way being approached, and to eliminate the occurrence of a zone of darkness in the immediate front of the automobile resulting from the use of the illuminating means now in common use. This is accomplished by 55 providing a greater scope of oscillation to the reflector 3, than that of the actuating means comprising the axle arm 21, and for the purpose of illustration attention may be called to the extent of the sector of the arc 60 traversed by each.

In the preferred embodiment of our invention as illustrated in the drawing, the extreme scope of oscillation of the axle arm 21, is through an arc of thirty-five degrees. This same movement of the axle arm 21 70 causes an oscillation of the reflector 3, through an arc of forty-five degrees.

It is to be understood, however, that we do not limit our invention to the proportionate degree of variation of movement, as 75 other proportions may be applied, without departing from the spirit of our invention.

What we accomplish by the means illustrated is a divergence of the projected light, in advance of the divergence of the automobile, in rounding a curve in the roadway, 80 whereby every sector of the curve traversed by the automobile has been adequately illuminated in advance.

Having described our invention, what we 85 claim as new and desire to secure by Letters Patent, is:

1. In combination with an automobile and the steering knuckles thereof, a rack carried by one of said knuckles, a lamp case 90 rigidly mounted on said automobile, a reflector mounted for oscillating movement within said lamp case, a flexible shaft connected to said reflector having a pinion mounted thereon and adapted to mesh with 95 the rack carried by the knuckle and to actuate the oscillation of the reflector within the case, with, but at a greater angle than the steering knuckle.

2. In combination with an automobile 100 and the steering mechanism thereof including the front wheel knuckles, a bracket projecting from one of said knuckles, a spring controlled longitudinally and transversely movable rack bar pivoted on said bracket, 105 a fixed lamp housing carried by the automobile, a reflector mounted for oscillating movement within said housing, a shaft detachably connected to said reflector, a pinion mounted on said shaft, means to 110 yieldingly hold the rack in mesh with said pinion whereby the reflector is oscillated within the lamp housing, with, but at a greater angle than the steering knuckle.

3. In combination with an automobile 115 and the steering knuckle thereof, a bracket projecting from said knuckle, a spring controlled longitudinally and transversely movable rack bar pivoted on said bracket, a fixed lamp housing mounted on said automobile, 120 a reflector mounted for oscillating movement in a horizontal plane within said housing, a shaft detachably connected to said reflector having a pinion mounted thereon and adapted to be placed in and out of mesh with said 125 rack bar, and means to maintain the reflector stationary within the lamp housing while the rack bar and pinion are out of mesh.

4. A headlight of the character described comprising a fixed lamp casing mounted on 130

an automobile, a reflector mounted for oscillating movement therein, a flexible operating shaft connected to one of the pivots of the reflector, a steering knuckle mounted for 5 rotative movement, a gear actuating rack operatively connected to said knuckle and an operative gear mounted on said flexible shaft in mesh with and adapted to be rotated by said actuating rack whereby the 10 reflector will be moved in the same direction

with, but at a greater angle than the steering knuckle.

In testimony whereof we have affixed our signatures in the presence of two witnesses.

NORMAN E. PHILLIPS.
JAMES E. MATHERS.
